US00D966063S

(12) **United States Design Patent** (10) **Patent No.:** **US D966,063 S**
Kukucka et al. (45) **Date of Patent:** **** Oct. 11, 2022**

(54) **SOCKET**(71) Applicant: **GRIP HOLDINGS LLC**, Brandon, FL (US)(72) Inventors: **Paul Kukucka**, Brandon, FL (US); **Thomas Stefan Kukucka**, Brandon, FL (US)(73) Assignee: **GRIP HOLDINGS LLC**, Brandon, FL (US)(**) Term: **15 Years**(21) Appl. No.: **29/754,192**(22) Filed: **Oct. 7, 2020****Related U.S. Application Data**

(63) Continuation-in-part of application No. 17/006,272, filed on Aug. 28, 2020, now Pat. No. 11,103,983, which is a continuation-in-part of application No. 16/033,970, filed on Jul. 12, 2018, now Pat. No. 10,786,890.

(60) Provisional application No. 62/639,619, filed on Mar. 7, 2018, provisional application No. 62/531,828, filed on Jul. 12, 2019.

(51) **LOC (13) Cl.** ..... **08-05**(52) **U.S. Cl.**USPC ..... **D8/29**(58) **Field of Classification Search**USPC D8/21, 25, 28, 29
CPC B25B 13/06; B25B 13/065; B25B 23/0035

Primary Examiner — Rachel A. Voorhies*Assistant Examiner* — Benjamin D. Wannemacher(57) **CLAIM**

The ornamental design for a socket, as shown and described.

DESCRIPTION

FIG. 1 is a front top perspective view of a socket showing my new design;

FIG. 2 is a front elevational view thereof;

FIG. 3 is a rear elevational view thereof;

FIG. 4 is a cross sectional view taken along the line 4-4 in FIG. 3;

FIG. 5 is a right side elevational view thereof;

FIG. 6 is a left side elevational view thereof;

FIG. 7 is a top plan view thereof; and,

FIG. 8 is a bottom plan view thereof.

The broken lines in FIGS. 1-8 are included for the purpose of illustrating environmental structure and form no part of the claimed design.

1 Claim, 8 Drawing Sheets# US D966,063 S
